FIG. 3.

INVENTOR:
Charles Hammon.
BY his ATTORNEY:
A. M. Carlsen.

UNITED STATES PATENT OFFICE.

CHARLES HAMMON, OF STILLWATER, MINNESOTA.

POCKET-SAFE.

1,098,496.

Specification of Letters Patent.

Patented June 2, 1914.

Application filed May 23, 1913. Serial No. 769,461.

To all whom it may concern:

Be it known that I, CHARLES HAMMON, a citizen of the United States, residing at Stillwater, in the county of Washington and 5 State of Minnesota, have invented a new and useful Pocket-Safe, of which the following is a specification.

My invention relates to pocket safes; and the object of the invention is to prevent the 10 unnoticed removal of purses and other valuables from a garment pocket by pickpocket or other thieves, or by accidentally inverting the pocket. To attain this object I provide a metallic safe adapted to go into a pocket 15 and to be secured therein in such a manner that it cannot be removed without first opening the safe. I also provide the safe with an alarm bell which is automatically rung by opening the safe. I also construct the 20 safe in such a manner that it is difficult to open without arousing the carrier of the safe even if the bell should be put out of commission by the thief, or should accidentally get out of order.

25 In the accompanying drawings,—Figure 1 is a top view of my pocket safe. Fig. 2 is a section on the line *a—a* Fig. 1 of the upper portion of the safe. Fig. 3 is a section on the line *b—b* Fig. 1, of the upper portion 30 of the safe. Fig. 4 is an inner side view of a portion of a coat having an inside pocket with my improved safe secured therein. Fig. 5 is a vertical section on the line *c—c* Fig. 4 with the spring 19 in Fig. 3 omitted. 35 Fig. 6 is a section on the line *e—e* Fig. 3. Fig. 7 is a section on the line *d—d* Fig. 3.

Referring to the drawing by reference numerals, 1 designates a sheet metallic box or body of the safe and is adapted to be 40 slipped into a garment pocket, preferably an inside coat pocket as shown in Figs. 4 and 5, where 2 designates the coat, 3 the lining, and 4 the pocket.

To the upper edge of the inner wall of 45 the box (that is, the wall next-to the person carrying the safe) is hinged by a pintle 5 a flap 6, which is provided with two prongs 7, which prongs are adapted to pass through eyelets (not shown) in the wall 4^x of the 50 pocket, and through apertures 9 in the adjacent wall 1^x of the box (see Fig. 2). Said prongs are each provided with a transverse aperture 8 (see dotted line 8 in Fig. 5) for the reception of the end of a locking bolt 10

(see Fig. 2) sliding in bearings 11 and provided with a finger catch 12.

Upon the adjacent ends of the two bolts is placed an expansion coil spring 13, which acts against the finger catches to hold the bolts in locking position. Hence to remove 60 the safe a person must put two fingers down into the safe and retract the bolts 10 by pulling the finger catches against the stopping pins 14.

The cover 15 is hinged on the same pintle, 65 5, and does not only cover the top of the box, but has also a rigid angular downward extension 15^x covering a large segmental notch 16 in the outer wall 1^{xx} of the box (see Fig. 3). To said extension 15^x is pivoted at 70 17 a lever 18, which by a spring 19 is normally held in one end of a slot 20 in the cover. The lever 18 projects above the cover and is provided with a slotted hole 21 in which is inserted the operating arm 22 of a 75 bell 23, which is mounted in the present illustration upon the cover, while it may if so desired be mounted at the under side of the cover so as to prevent muffling of it by a pickpocket. Said bell is on the order of a 80 common bicycle bell which rings when the operating lever is vibrated or even pressed only to one side.

The lower end of the lever 18 is arranged to engage and open a latch 24, which is pivoted at 25 to the box and in locking the cover engages a hook 26 on the part 15^x of the cover. Said latch 24 swings in a keeper 27 and is normally held in locking position by a spring 28. From this arrangement it 90 will be seen that in opening the safe the upper end of the lever 18 is to be pressed as from left to right in Fig. 3, which movement will ring the bell and disengage the latch 24, whereupon a spring 29 (shown to 95 the left in Fig. 3) will start the opening of the cover by pressing outward against the portion 15^x of it. Said spring 29 thus holds the cover unlocked until the operator can take hold of it and open it fully, as shown 100 in dotted lines in Fig. 5. The latter movement of the cover is intentionally rendered somewhat difficult by having the extension 15^x of the cover so long that it requires about all available space in the pocket to 105 open it and close it, as indicated to the fullest extent by the circle 30 in Fig. 5.

The notch 16 in the rear wall of the box

facilitates the placing and the removing of the contents of the box. Still where the box is of the deepest type there might be some difficulty in reaching all of its contents; for that reason I provide the box with a false bottom 31 (see Fig. 5) from which extends upwardly a flat rod 32 (see Figs. 3 and 5) having at its upper end a hook 33 for taking hold of in raising the false bottom to any desired height. 34 (in Fig. 3) is a spring arm clasping the rod 32 against the wall of the box, so as to hold the false bottom at the desired elevations while placing upon it or removing from it, jew- 15 elry, watches, cash, or pocket books, and other valuables carried in the safe. Before the safe is closed the rod 32 is pushed down until the false bottom 31 may rest upon the fixed bottom 31^x.

20 It is of course possible to omit either one of the two bottoms 31 31^x, but it is probably preferable to use both of them.

What I claim is:—

25 1. In a pocket safe, the combination with a metallic box open at the top and provided with means for securing it in a garment pocket, of a cover hinged on the box to cover said open top, a device for locking the cover after it is closed and unlocking it

preparatory to opening it, and an audible 30 signal device arranged to be automatically operated by said unlocking device.

2. In a pocket safe, the combination with a metallic box open at the top and pro- 35 vided with means for securing it in a garment pocket, of a cover hinged to the box to close said opening; said cover having the edge opposite from its hinges provided with an angular extension reaching partly down upon the side of the box when the 40 cover is closed, such arm designed to render unwarranted opening of the cover difficult.

3. In a pocket safe, the combination with a box open at the top and having means for securing it in a garment pocket, and a 45 cover closing its top, of a bottom movable up and down in the box, and means for holding said bottom at different heights in the box, so as to avoid detaching and in- 50 verting of the box in order to reach the lower part of its contents.

In testimony whereof I affix my signature, in presence of two witnesses.

CHARLES HAMMON.
